LIGHTER

Marcel Quercia, Paris, France, assignor to Flaminaire
Marcel Quercia, Paris, France

Filed Dec. 22, 1967, Ser. No. 9,897

Claims priority, application France July 3, 1967

Term of patent 7 years

Int. Cl. D27—05

U.S. Cl. D48—27

Fig.1.

Fig.2.

Fig.3.

Fig.4.

Fig.5.

FIGS. 1 and 2 are two elevational views of the lighter at 90° from each other respectively;

FIG. 3 is a top view;

FIG. 4 is a bottom view;

FIG. 5 is a perspective view showing the lighter from below.

The dominant features of my design reside in the portions shown in full lines.

I claim:

The ornamental design for a lighter, substantially as shown and described.
